Charles R. Searle

UNITED STATES PATENT OFFICE.

JOHN W. BECKMANN, OF NEW YORK, N. Y., ASSIGNOR OF ONE-HALF TO J. WALTER REMBE, OF PEEKSKILL, NEW YORK.

TOILET-POWDER CONTAINER.

1,193,223.

Specification of Letters Patent. Patented Aug. 1, 1916.

Application filed October 5, 1915. Serial No. 54,141.

To all whom it may concern:

Be it known that I, JOHN W. BECKMANN, a citizen of the United States, residing at Richmond Hill, Long Island, in the city of New York, borough of Queens, in the county of Queens and State of New York, have invented a certain new and useful Improvement in Toilet-Powder Containers, of which the following is a specification.

10 The invention relates to receptacles for face powder and analogous material, and the object of the invention is to provide an inexpensive container and dispenser in which the powder may be sold, having a simple controlling device by which the contents may be delivered in the desired quantities without danger of leakage, and in the complete form of the invention, provided with a powder-puff and mirror attached to 20 and forming part of the closure for the container.

25 The invention consists in certain details of construction and arrangement by which the above objects are attained, to be hereinafter described and claimed.

The accompanying drawings form a part of this specification and show an approved form of the invention.

Figure 1 is a side elevation of the improved container. Fig. 2 is a corresponding axial section, partly in elevation. Fig. 3 is a side elevation of the closure. Fig. 4 is a plan view of the upper face of the closure. Fig. 5 is a transverse section through the container, taken on the line 6—6 in Fig. 2 and seen in the direction indicated by the arrows. Fig. 6 is an elevation of the controlling valve alone.

Similar letters of reference indicate the 40 same parts in all the figures.

A is the cylindrical body of the container, closed at the upper end by a cap B inclosing the body and secured thereto by the engagement of the flange B¹ in an annular groove a. The cap is slightly coned, as shown, and terminates in a circular extension or chamber B² having a central aperture for the protruding end of a valve-rod D¹ and containing a felt washer G or other simple packing ring cemented in the chamber and adapted to prevent the escape of powder M around such rod.

Within the body A, above the lower end of the latter, is a false bottom or diaphragm C downwardly coned to facilitate the down-

ward flow of powder, and held by the engagement of its circular margin in an annular groove a¹. At the center of the diaphragm is a circular valve-opening receiving a downwardly-opening conical valve D matching thereto and arranged when forced downwardly from the valve-opening or seat to permit the delivery of powder; the extent of such downward movement of the valve-rod D¹ is limited by the contact of a cap or pushbutton D² on the protruding upper end of the rod, with the upper face of the extension B².

The valve D is held normally closed by a helical spring E inclosing the lower portion of the rod and abutting at one end against the upper face of the diaphragm C, and attached at the other end to the valve-rod.

The open lower end of the body A is closed by a removable cover comprising a ring F received therein and having a horizontal flange F¹ folded upon itself to produce an annular groove receiving and holding a disk F² which is preferably a glass mirror, the whole forming a cup adapted to be thrust upwardly into the open lower end of the body A to serve as a closure therefor.

On the lower margin or skirt of the body at opposite locations are inverted L-shaped indentations or channels A³ adapted to receive similarly located points or projections F³ on the ring F and thus lock the cover in place in the well-known manner analogous to a bayonet connection.

Within the cover and cemented to the inner face of the mirror F² is a tuft of wool or the like extending above the ring F and serving as a powder puff N. The puff also serves as a packing to prevent leakage of powder through the joint between the body and cover.

As the whole is intended to be sold as a powder package and discarded when the contents are exhausted, it is imperative that the construction be extremely inexpensive, and it is also highly important that the powder be securely held to prevent leakage when carried by the user or transported in baggage. The valve-opening in the diaphragm C being formed by suitable dies offers a sharp edge of dependable regularity, against which the conical valve seats itself closely and is held in close contact therewith by the expansive force of the spring E, thus afford-

ing a reliable cut-off for the powder. The lower convolution of the spring terminates in an outwardly extending arm E¹, see Figs. 2 and 5, of sufficient length to prevent the entrance or engagement of the spring into the valve-opening.

The valve D and its stem or rod D¹ are preferably formed integrally from a single piece of wire by an upsetting process analogous to that by which the heads of wire nails are produced, and in the process of manufacture two spurs or outwardly and downwardly projecting prongs D² D³ are formed, see Fig. 6, receiving in their angles the upper convolution of the spring E, which are then bent inwardly upon the wire of the spring to hold the upper end of the latter, as shown in Fig. 2.

The cap or button D² is stamped to shape and forced upon the upper end of the valve-rod to engage therewith frictionally. Downward pressure upon the button forces the valve D from its seat in the valve-opening and delivers a small quantity of powder through the annular orifice thus produced, and the compression of the spring thus induced moves each of its convolutions slightly but sufficiently to agitate the powder in the immediate vicinity of the valve-rod and valve-opening and insures a free flow.

Although the disk F² is described as a mirror, it may be of any material, and the puff N may be omitted, or the bottom of the body A may be left open and the powder received therethrough upon an independent puff or a substitute therefor.

The material of the container is preferably thin sheet metal, but other suitable materials may be employed.

It is proposed to make an extremely small size of the container, adapted to be conveniently carried in a purse or vanity-bag; it will be noted that the simple inexpensive construction shown permits such manufacture to be economically practicable.

I claim:—

1. In a device of the character described, a body having a top, a removable bottom

portion for said body, a false bottom retained within the body between the bottom and top, a spring-actuated valve rod movable through an opening in the top, and a valve carried by the lower end of the valve rod and disposed between the bottom of the body and the false bottom and adapted to seat against the latter.

2. In a device of the character described, a body having a top, a removable bottom portion for said body, a false bottom retained within the body between the bottom and top, a spring-actuated valve rod movable through an opening in the top, a valve carried by the lower end of the valve rod and disposed between the bottom of the body and the false bottom and adapted to seat against the latter, and means on the valve rod exteriorly of the top to engage the latter and limit the opening movement of the valve.

3. A device of the character described comprising a body, a conical cover therefor, a removable bottom therefor, a conical diaphragm within the body between the bottom and top and having an opening with valve seat, a valve adapted to said seat from the under side of the diaphragm, a valve rod carrying said valve and guided in the cover and a spring around said rod within the body having one end secured to the rod and the other bearing against said diaphragm.

4. A device of the character described comprising a body, a removable bottom therefor, a top therefor, a removable conical diaphragm within the body having an opening and valve seat, a valve fitted to said seat from the under side of the diaphragm, a valve rod carrying the valve and movable through the top and a spring around said valve rod within the body with one end secured to said rod and the inner end having its lower convolution terminating in an outwardly extending arm engaging the diaphragm and preventing the entrance of the spring into the valve opening.

In testimony that I claim the invention above set forth I affix my signature.

JOHN W. BECKMANN.
